Attorney.

UNITED STATES PATENT OFFICE.

CLARENCE O. HAWXHURST, OF ST. LOUIS, MISSOURI.

INDICATOR.

1,290,988.

Specification of Letters Patent. Patented Jan. 14, 1919.

Application filed October 23, 1916. Serial No. 127,161.

To all whom it may concern:

Be it known that I, CLARENCE O. HAWXHURST, a citizen of the United States, residing in the city of St. Louis and State of Missouri, have invented certain new and useful Improvements in Indicators, of which the following is a specification.

My invention relates to an office indicator, and more particularly to a device so constructed that it may be manually operated to indicate the absence of a proprietor and when he or she will return, or similar information, and provide means to enable callers to leave cards or messages.

A further object of the invention is to provide a device of comparatively few parts, inexpensive in manufacture, attractive and neat in appearance, easily and quickly adjusted, durable, and capable of being attached to a door or window or station upon a desk, or other suitable place.

With the above and other objects in view, the invention consists in the novel construction, arrangement and combination of parts as will be fully described hereinafter, and finally pointed out in the claim hereto appended:

Referring to the accompanying drawings forming a part of this specification wherein like characters of reference denote similar parts throughout the several views:

Figure 1 is a front elevation of my improved office indicator.

Fig. 2 is a vertical sectional view thereof.

Fig. 3 is a detail in perspective clearly showing the card and pencil-holder.

In carrying out the aim of my present invention I employ a plate 1 consisting preferably of a rectangular wooden body of any suitable dimensions.

The board 1 is provided adjacent its upper edge with a longitudinal slotted opening 2, and near its lower edge with a longitudinal slotted opening 3.

A revoluble plate 4 is adapted to be positioned in the slotted opening 2 and supported by means of the pintles 5 which are frictionally journaled in the board 1. One of the pintles is provided with a knob 6 for turning the plate 4.

A second revoluble plate 7 is adapted to be positioned in the slotted opening 3 and supported by means of the pintles 8, which are frictionally positioned in the board 1.

One of these pintles 8 is also provided with a knob 9 for turning the plate 7.

The above plates 4 and 7 may be of any other design than flat, as shown, and may be triangular in cross-section to provide a plurality of faces adapted to bear information such, for instance, as printed data.

Centrally arranged upon the board 1 intermediate the upper and lower slotted openings 2 and 3 is a dial plate 10. This plate 10 is provided in concentric formation with figures 1 to 12 to indicate the hours of the day and designated 11, and preferably with dashes 12 and 13 to indicate the quarter and half hours, respectively. The hour figures are arranged in the outer circle.

The figures 1 to 31 in the center circle designated 14 indicate the dates of the month.

The names of the days of the week in the inner circle designated 15, are preferably abbreviated.

Fixed to the center of the dial plate 10 is a supporting pin 16. Movable mounted upon the pin 16 are three clock hands 17, 18 and 19 to indicate the hour, date and day, respectively.

A resilient card-holder is arranged at each end of the board 1 adjacent the sides of the dial plate 10 comprising a flange 20, the body 21, and the resilient wall 22 having the upper edge terminating in a rolled or cylindrical body forming a pencil-holder 23. The flange 20 of each of these holders is secured to the face of the board 1 by means of suitable fastening devices such, for instance, as screws.

It will be observed that when the proprietor desires to leave the office the device is set to indicate the proprietor's return. For an example, as illustrated, the revolving plates and hands indicate that the proprietor will return at two-fifteen, on the 15th day of the month, which is indicated as Saturday.

The opposite faces of the revoluble plates 2 and 3 may be provided with the word In and the hours of the day, respectively, or any other data or information desired.

The operation or adjustment of the indicator is simple and quick. All the operator needs to do is to turn the knobs 6 and 9 to revolve the plates 2 and 3, and to move the several hands by means of the index finger.

The device may be hung or attached to the door or wall in any suitable manner, or left to stand upon a desk or table, if desired.

If desired, the one card-holder may be filled with blank cards, designated 24, by

the proprietor, and after a message has been written by a caller on one of these cards it may be deposited in the other holder, as indicated by dotted lines.

5 Suitable printed data may be stamped or otherwise placed upon the walls 22 of the card-holders, if desired. This printed data may be in the nature of advertising, or other information, if desired.

10 The various advantages of this particular device will readily suggest themselves to those skilled in the art to which it appertains.

What I claim is:

15 An office indicator composed of a base having a slotted opening near its upper edge

and a slotted opening near its lower edge, a plate bearing suitable data revolubly mounted within the upper opening to permit either side thereof to be exposed to view, a plate 20 bearing suitable data revolubly mounted within said lower opening to permit either side thereof to be exposed to view, an information dial arranged between said revoluble plates, a plurality of hands for said dial and 25 a resilient card holder arranged on each side of said dial and between the two revoluble plates, the upper ends of which are each curved to provide a tubular pencil holder.

In testimony whereof I have hereunto 30 signed my name to the specification.

CLARENCE O. HAWXHURST.
